DECORATIVE SPECTACLE HINGE ELEMENT

Richard L. Huggins, Lima, N.Y., assignor to Bausch & Lomb Incorporated, Rochester, N.Y., a corporation of New York

Filed Apr. 1, 1969, Ser. No. 16,526

Term of patent 14 years

Int. Cl. D16—08

U.S. Cl. D57—1

FIG. 1

FIG. 2

FIG. 3

FIG. 4

FIG. 1 is a front view of the decorative spectacle hinge element embodying my new design, the spectacle frame and second hinge element being shown for illustrative purposes only;

FIG. 2 is a front view of the hinge element shown on an enlarged scale;

FIG. 3 is a right side view as taken in FIG. 2; and

FIG. 4 is a top plan view thereof.

I claim:

The new and ornamental design for a decorative spectacle hinge element, substantially as shown and described.
